(57) **CLAIM**

The ornamental design for a toothpaste dispensing travel toothbrush, as shown and described.

DESCRIPTION

FIG. 1 is a top, right-side perspective view of a toothpaste dispensing travel toothbrush, showing my new design; FIG. 2 is a bottom, left-side perspective view thereof; FIG. 3 is a front-side view thereof; FIG. 4 is a rear-side view thereof; FIG. 5 is a right-side view thereof; FIG. 6 is a left-side view thereof; FIG. 7 is a bottom-side view thereof; FIG. 8 is a top-side view thereof; FIG. 9 is a cross-section view taken along line 9-9 shown in FIG. 8;

FIG. 10 is a top, right side perspective view of the inner member of the toothpaste dispensing travel toothbrush, shown separately to show portions of the design not clearly visible when combined;

FIG. 11 is a bottom, left-side perspective view thereof; FIG. 12 is a top, right side perspective view of the outer member of the toothpaste dispensing travel toothbrush, shown separately to show portions of the design not clearly visible when combined;

FIG. 13 is a top, right-side perspective view thereof; and, FIG. 14 is an enlarged view of portion 14 shown in FIG. 9. The broken lines in the drawings show enlarged view indicators, and form no part of the claimed design.
